[57] CLAIM

The ornamental design for a thermal pizza bag, as shown and described.

DESCRIPTION

FIG. 1 is a left side perspective view of a thermal pizza bag showing our new design, unfolded, and with the resealable flap in the partially open position;

FIG. 2 is a front perspective view thereof, with the resealable flap in the closed position;

FIG. 3 is a front elevational view thereof, with the thermal pizza bag in the folded condition;

FIG. 4 is a top plan view thereof, with the resealable flap in the fully open position;

FIG. 5 is a left side elevational view thereof, with the resealable flap in the fully opened position;

FIG. 6 is a right side elevational view thereof, with the resealable flap in the fully opened position;

FIG. 7 is a bottom plan view thereof, with the resealable flap in the fully opened position;

FIG. 8 is a back elevational view thereof; and,

FIG. 9 is a front elevational view thereof, with the resealable flap in the fully opened position.
